UNITED STATES PATENT OFFICE.

JAMES B. McGINLEY, OF ALLEGHENY, PENNSYLVANIA, ASSIGNOR TO CROWN FIRE EXTINGUISHER COMPANY, OF PITTSBURG, PENNSYLVANIA, A COPARTNERSHIP.

VALVE FOR FIRE-SPRINKLER SYSTEMS.

No. 884,841.

Specification of Letters Patent. Patented April 14, 1908.

Application filed June 29, 1907. Serial No. 381,434.

To all whom it may concern:

Be it known that I, JAMES B. McGINLEY, a citizen of the United States of America, residing at Allegheny, in the county of Allegheny and State of Pennsylvania, have invented certain new and useful Improvements in Valves for Fire - Sprinkler Systems, of which the following is a specification, reference being had therein to the accompanying drawing.

This invention relates to valves for fire sprinkler systems and its object is to provide improved means for automatically opening a valve to permit water to pass through the sprinkler pipes.

A further object of the invention is to combine with an automatically-operating water-controlling valve an alarm device comprising a piston, and electrical contact points adapted to be bridged by said piston to complete an electric circuit to an audible alarm.

The construction of the improvement will be fully described hereinafter in connection with the accompanying drawing which forms part of this specification and its novel features will be defined in the appended claims.

In the drawing, Figure 1 is a vertical sectional elevation of a valve and alarm device embodying the invention, Fig. 2 is a transverse section of the same on the line $x-x$ of Fig. 1 looking toward the right, Fig. 3 is a section on the line $x-x$ looking toward the left and Fig. 4 is a vertical section on an enlarged scale of the alarm device shown in Fig. 1.

The reference 1 denotes a water supply pipe coupled at its upper end to a nipple 2 depending from a valve casing 3. The latter is formed of two different diameters and that portion of larger diameter of the casing 3 has mounted therein a cylindrical bushing 4. The nipple 3 constitutes a vertical water passage 6 with which the lower end of a curved water passage 5 communicates. The upper end of the water passage 5 opens into that portion of smaller diameter of the valve casing 3. Communicating with that portion of larger diameter of the valve casing 3 is a curved air passage 9 which has its upper end opening into a vertically-extending pipe 7. The pipe is arranged in alignment with the water passage 6 and opens into that portion of

larger diameter of the valve casing 3 as at 8. One end of the casing 3 is closed by a head 10, 55 and the opposite end by a head 11 provided on its inner surface with projecting lugs 12 serving as stops for a valve 13 movably supported within the casing and having a contracted stem 13^a operating in that portion 60 of smaller diameter of the casing 3.

Rising from one end of the casing 3 is a water pipe 14 provided with an indicating gage 15, and at the opposite end of said casing is an air pipe 16 equipped with an indicating gage 17. The casing 3 is also provided with an alarm device comprising a water pipe 18 communicating with the water passage 5 and supporting at its upper end a cylindrical chamber 19 within which is a piston 20 formed with an annular depending flange 21 and a central upwardly projecting pin 22. The chamber 19 is provided with a cover 23 through which extends an insulated binding post 24 carrying spring contact 75 fingers 25, and connected to electrical conductors 26 in circuit with an audible alarm (not shown).

The utility and operation of the mechanism constructed as thus described is as follows: The passages 7 and 9 and the interior of the casing 3 to the right of the valve 13 contain compressed air while the passages 5 and 6, and the space within the casing 3 to the left of the valve 13 contain water under 85 pressure. The air pressure is less than the water pressure, but the air area at one end of the valve 13 is greater than the water area at the stem end of the valve, and as a consequence, the valve 13 is normally in the position shown in Fig. 1, closing the water passage 6 at its upper end and also the lower end of the passage 8.

In case of fire a thermostat or similar device effected by heat (not shown) operates to 95 exhaust the air pressure, whereupon the water pressure forces the valve 13 to the right opening the passages 6 and 8 and closing communication between the casing and the passage 9. This permits the water to flow up through the passages 5 and 6 to the passage 7 and from thence to the sprinkler pipes. The inward movement of the valve 13 withdraws the valve stem from the lower end of the pipe 18 permitting water to flow up 100 through said pipe to raise the piston 20 thus

bringing the pin 22 into contact with the spring contacts 25 to close a circuit to the alarm device through the conductors 26.

To facilitate draining the casing 3, I provide a pipe 27 at the bottom of the casing provided with a stop cock 28.

The valve 13 may be solid or hollow as desired, and I would have it understood that the invention includes all such variations and 10 modifications in the details of construction as may be resorted to without departing from the terms and scope of the claims.

What I claim and desire to secure by Letters Patent, is:—

sure when the air pressure is reduced, thereby establishing communication between said vertically aligned passages, and a plurality of lugs extending in that portion of larger diameter of the valve chamber at one end thereof and adapted to limit the movement of the valvular member in one direction.

In testimony whereof I affix my signature in the presence of two witnesses.

JAMES B. McGINLEY.
